Republic of South Africa

Filed Aug. 27, 1962, Ser. No. 219,797

Claims priority, application Great Britain Nov. 23, 1959
38 Claims. (Cl. 70—150)

This invention relates to fastening devices such as lockable latches used on doors, windows and the like of the kind having fixed handles and push button means for causing retraction of the latch bolt or the like.

This application is a continuation-in-part of applications Serial No. 68,900, filed November 14, 1960, now abandoned, and Serial No. 179,574, filed March 14, 1962.

This invention is of particular application on a lockable fastening device of the kind in which a spring biased latch bolt is retracted by a transversely positioned actuating or operating slide and which bolt and slide provide coacting means to cause retraction of the bolt by a wedging-like action on forced axial displacement of the slide while, and in which rotatable means are associated with the slide for locking the fastening device, rotation of the said means being imparted thereto by a key operated rotatable lock and/or rotatable push button or like means provided on or at the ends of the slide. This type of fastening device is received in two intersecting holes bored into the door, one hole being bored horizontally into the edge face of the door whereas the other is bored at right angles through such door with their axes intersecting and in the same horizontal plane. With said kind of fastening device, fixed handles are used which may also serve as guiding means for the said slide.

It is an object of this invention to provide a fastening device for doors of the aforesaid kind which is of robust construction and which may be used on doors in which the swinging edge is at the left- or at the right-hand side and opening inwardly or outwardly without such device requiring modifications or alterations.

It is an object of this invention to provide a lockable fastening device of the kind indicated which presents security against forcing of the fastening device, when it is locked, by hammering on an end of the slide.

A further object of the invention is to provide fastening devices in which the main component parts may remain unchanged and still the fastening devices will be capable of being placed in the non-locking or "dead locking" conditions (when only the slide is prevented from moving while the bolt remains displaceable against its biasing means), or which is capable of forming an emergency lock such as for use on bathrooms whereby such a door may be unlocked from the outside by a coin, screw driver or the like non-circular or simple means instead of a key, or which is capable of forming a "panic lock" which is openable without an unlocking action from one side when locked from the opposite side of the door.

A still further object resides in the provision of additional and optional means on such fastening devices whereby the security presented is increased.

A still further object is to provide key operating means which can be provided on either side of the door permitting, at any later stage, changing of the key operating means without the latch and locking means requiring replacement or alteration of any of the parts.

According to the invention, the fastening device comprises in combination a bolt casing and a spring biased latch bolt slidably mounted within said bolt casing. The end of said bolt within the casing has at least one arm extending in the axial direction from the end of said latch bolt, and said arm has a projection on the end thereof extending diametrically of said latch bolt and having two

2

converging faces on the side of the projection toward said bolt. A guided actuating slide extends transversely through the casing and adjacent said arm and between the latch bolt and the projection, and said actuating slide has a V-shaped recess in at least one longitudinal side of the slide, said V-shaped recess having two converging faces with which the converging faces of said projection engage for displacing the bolt in the direction of its axis on displacement of the slide in the direction of its own axis.

10 The slide has an axial bore therethrough intersecting the V-shaped recess at a point spaced from the apex thereof, and a rod-like element is located in the bore of said actuating slide and is rotatable about its axis at least through 90°. This rod-like element has a portion of reduced cross sectional shape along a part of its length having a dimension at least in one direction transverse to the length of the rod-like element no greater than the distance from the end of said projection on said latch bolt arm to the bottom of the axial bore in said actuating slide. The reduced cross sectional portion in one rotational position of said rod-like element allows passage of said projection on said arm past said rod-like element. There is at least one projection on said rod-like element extending in a direction transverse to the length of said rod-like element and perpendicular to the said one direction which is engageable with a part of said fastening device other than said slide to block movement of said slide relative to said latch bolt when said rod-like element is in another rotational position 90° from said first rotational position.

30 In order that the invention may be clearly understood, reference will now be made to the accompanying sheets of drawings on which the same reference numerals are used for the same parts of the fastening device.

In the drawings:

FIGURE 33 is a view similar to FIGURE 32 showing a form of handle for use on the other side of the fastening device shown in FIGURES 12, 13 and 14; and

FIGURE 34 is a plan of a modified form of slide having weakened regions for breaking away to form stop abutment faces when the fastening device is in the locked position and on application of an excessive impulse on one end of the slide or associated parts.

Referring to the drawings, reference numeral 1 denotes the latch bolt, which also forms the locking bolt for the door fastening device. The bolt 1, which is of generally cylindrical shape and having the usual curved or flat taper 1a on the end projecting from the door, has two parallel spaced axially arranged extensions or arms 2 extending from diametrically opposite positions on the end of the latch, which arms are of reduced width and have on their free ends perpendicular projections 3 extending toward each other and which terminate with the ends in spaced relationship and opposed to one an-

other. The bolt 1 and extensions 2 are slidable within a cylindrical casing 4 and which casing is fitted into a hole-like recess bored into the side edge of a door 5. One side of the bolt 1 has a flat surface 6 for slidably engaging a correspondingly shaped internal surface 7 of the casing 4. The region of the casing opposite to the end from which the bolt 1 projects has a parallel walled cavity 8 therein in which the extensions 2 and perpendicular projections 3 are guided in sliding fashion. Within the casing 4 is a disc 10 extending transversely of the casing and having projections 64 and 101 on opposite ends, the projection 64 forming a curved ended detent for engaging a centrally disposed depression 63 provided in an actuating slide 13 to be described hereinafter. The projection 101 forms a retaining pin for a compression spring 11 which is also retained at the opposite end by extension 102 on the bolt 1. Said spring normally retains the bolt 1 resiliently in its outwardly extended position and simultaneously maintains engagement of the detent forming projection 64 with the slide 13.

The casing 4 also has transverse openings 12 in diametrically opposed sides thereof in which a guided actuating slide 13 for actuating the bolt is transversely located and guided.

In the embodiment of FIGS. 1-7, the actuating slide 13 comprises a bar-like member of substantially rectangular cross-sectional shape from one end of which a tubular extension 19 projects. In the opposite major faces 104 of the slide 13 similar V-shaped recesses 15 are provided at corresponding positions and which recesses both have converging wall-like faces 16 which converge in the direction of the side edge of the door 5 from which the bolt projects. The faces 16 of the recesses 15 are engaged by complementary converging faces 16a on the side of projections 3 which face the bolt 1.

The slide 13 has an axial bore 103 therethrough which extends throughout the length of the slide 13 and which communicates with the bore of the tubular extension 19. In said bore 103 is a rod-like element in the form of a latch bolt locking rod 105. The rod 105 is rotatable in the bore and extends beyond the ends of the slide 13, the one end terminating within the bore of the tubular extension 19. One end part of the rod 105 is of cylindrical shape (or other shape which permits it to be rotatable in bore 103) whereas the remaining portion 107, forming the major portion of such rod, has a reduced cross-sectional shape which is formed by removing material from diametrically opposite sides of the rod to form two flat surfaces 106, such reduced part 107 having a thickness equal to or slightly less than the thickness of the material web 108 separating the V-shaped recesses 15 in the slide 13. In said part 107 a pair of spaced transverse and obliquely located notches 109 are provided. The axial bore 103, at the regions where it opens out of the oblique faces 16 of one or both V-shaped recesses 15 is blocked by a sector shaped piece 110 (see FIGURE 2) which is adapted to be engaged by the notches 109. Said reduced regions of the bore 103 are engaged by the flat or reduced part 107 of the rod 105. Rotation of the rod 105 is limited to movement through an angle of 90° only by said pieces 110. In order to lock the bolt 1 in the extended position, rod 105 is turned so that the reduced part 107 is in a substantially vertical position so that it extends across the V-shaped recesses. The larger dimension of the reduced part 107 is greater than the distance between the ends of projections 3 so that the projections 3 cannot move past the rod part 107 and become locked in the converging or apex ends of such recesses. The smaller dimension of the reduced part 107 is less than the distance between the ends of projections 3, so that when the faces 106 of the part 107 are in line with the faces 111 of the recesses 15, the bolt is free to slide when the actuating slide 13 is moved in the direction of its own axis which is at right angles to the axis of the bolt assembly.

The slide 13 has a depression 63 in the side thereof directed towards the bolt 1 for engagement by the detent 64, whereby the sliding movement of the slide 13 is prevented or restrained when the door is slammed shut and the bolt is forcibly displaced inwardly and the reaction force of the spring 11 on the slide, by means of the disc 10 and detent 64, is increased.

The rod 105 has, on the cylindrical region to be located immediately inwardly of the end 112 of slide 13, two recessed flats 113 arranged at right angles to one another and which flats are adapted to be engaged by a flat or slightly curved leaf spring (not shown) which has the ends thereof tightly fitted into cavities 114 provided in the slide 13 and communicating with the bore 103. The resilient engagement of the spring on either of the flats 113 resists movement of the rod 105 from one alternative position to the other alternative position and in addition resists the withdrawal of the rod 105 from the slide 13. The extreme end 115 of rod 105, i.e. the end part extending from end 112 of slide 13, is of non-circular shape as at 116 for non-rotatable engagement in a complementarily shaped bottom of an axial hole provided in a knob 24. The said knob 24 engages the rod 105 tightly so that the rod rotates with the knob, while removal of the knob from the rod is prevented.

The knob 24 is of cylindrical shape and has a circumferential flange 117 on or near its holed end, whereas the opposite end is preferably dished as at 118 to form a press button whereby the sliding action can be imparted to the actuating slide 13. Said knob can be fixed to the rod 105 by means of a fixing screw or clip which is not shown.

The tubular extension 19 of the slide 13 has the barrel 40 of a cylindrical lock engaged therein, and it has two diametrically opposed grooves 44 for engagement and locking therein of the wafers 43 of the lock barrel. The lock barrel 40, in addition has a further wafer 120 (see FIGURES 1, 4, 10 and 11) which is not engaged or operated by the key but which forms a coupling for the connection of the lock barrel 40 to the end of the rod 105 projecting into the tubular extension 19. The wafer 120 in addition serves as a means to ensure that, on insertion of the key, the lock barrel 40 can only be rotated in the specific direction required for movement of the rod to the desired alternate position, such action being required by the position of the rod 105 in the slide 13.

The end 121 of rod 105 (FIGURE 6), is halved as at 122 and bevelled as at 123, while inwardly of the halved portion it is provided with connected notches 124 in two adjacent sides. The inner end of the lock barrel 40 has an axial hole 125 (FIGURES 4, 10 and 11) and an arcuate extension 126, while within the hole 125 and on the extension 126 a corner forming projection 127 is provided which has two faces 128 at right angles relative to one another. The wafer 120 is slidable diametrically in the lock barrel 40 and has oblique ends 129 arranged convergently relative to one another while the effective maximum length of the wafer 120 is the same as the diameter of the barrel 40. On one side of the wafer 120, a projection 130 is provided for engagement by a compression spring 131 (FIGURES 10 and 11), located in a recess or hole in the barrel 40 in order to bias the wafer 120 in one direction for engaging either of two transverse slots 132 (FIGURE 5) in the tubular extension 19. In the center region of the wafer, is a rectangular hole 133 in which the end 121 of the rod 105 engages by the reduced region of the rod 105. The wall forming sides of notches 124 engage the faces of the wafer 120 to prevent unintentional disengagement of the coupling formed by the rod end 121 and the barrel 40.

In either of the alternative positions of the rod 105 within the slide 13, one of the faces 106 adjacent the end 121 bears on one of the faces 128 of the barrel 40 eccentrically of the axis of the rod, so that when the barrel is rotated by a key either of such faces may cause rota-

tion of the rod 105 so that the rod 105 is caused to move to an alternative position. The rotational movement of the barrel is controlled by an end of the wafer 120 engaging a slot 132 of the tubular extension 19 while the oblique ends 129 of the wafer permit rotation of the barrel 40 in the required direction. The depth of the notches 124 is such that when the rod is in its locking position (FIGURE 11) the downwardly directed end of the wafer is operative in a slot 132 against the action of its spring.

In the circumferential surface of lock barrel 40 is an arcuate groove 135 which extends almost completely around the barrel 40. In said groove is positioned a coiled compression spring which is engaged at a position intermediate of its ends and between its convolutions by a projection (not shown) extending inwardly from the tubular extension 19 of the slide, so that the barrel 40 will automatically be returned to its key-receiving position, which is also its locked position. The use of a key is necessary for causing rotation of the rod 105 to its locked and unlocked positions from the outside of the door. From the inside of the door the locking and unlocking is effected by the turning of the knob 24.

The tubular extension 19 has a sleeve 136 therearound.

25 The sleeve 136 has a circumferential flange 137 at or near the end adjacent the door. The sleeve 136 and the knob 24 are each slidably located in an annular end 47 of a fixed door handle 46. In the outwardly directed end of the bore of the annular end 47 a shoulder 138 is provided. In the annular space between the bores of the handles 46 and the circumferential faces of the sleeve 136 and of the knob 24 are positioned compression springs 139 which bear on the shoulders 138 and flanges 137 and 117 to produce centering of the actuating slide 13 while the action of spring 11 is thereby assisted. In fact, with the use of springs 139, a light compression spring 11 can be used.

30 The shoulders 138 could be eliminated and the springs 139 arranged to press on the latch bolt casing 4 and flanges 117 and 137.

40 In operation, to unlatch the door, axially directed pressure is applied to either the knob 24 or the lock barrel 40 to cause axial displacement of the slide 13, whereupon the oblique faces effect a wedging and displacing action on the projections 3 on the ends of extensions 2 of bolt 1. Due to this wedging action, the projections 3 slide along converging faces 16 to cause retraction of the bolt. For locking of the bolt in the extended position, the rod 105 is rotated either by the knob 24 or the lock barrel 40. Rotation of such rod 105 is through an angle of 90° only.

45 A simplified construction is shown in FIGS. 8 and 9. As seen in FIG. 8, the V-shaped recess 15a extends into the actuating slide 13a from only one side, and it will be understood that only one projection 3 will then be necessary on the arm 2 on the bolt 1. The reduced portion 107a of the locking rod 105a is then flattened only on one side, and in this instance the minimum dimension of the portion 107a is less than the distance from the end of projection 3 to the bottom of the bore 103a in the slide, while the maximum dimension of the portion 107a is greater than said distance. The other parts of the actuating slide and locking rod are identical with the embodiment of FIGS. 1-6, and the operation of the locking device with the modified actuating slide and locking rod is also the same.

50 In the embodiment of FIGS. 12-17, the lockable fastening device for fitting in a door 151 consists of a latch bolt 152 which is of substantially circular cross-section and which has one flat side face 153 and a curved or sloping end 154 which normally projects beyond the side edge 155 of the door 151 for engaging a coacting striker plate which is of a known kind and is not illustrated. Said bolt 152 has two cantilever-like parallel arm-like extensions 156 projecting from diametrically opposite points on the end of the bolt opposite to the curved end 154 thereof. Each extension 156 has a perpendicular

projection 157 on the free end and which projections 157 extend towards one another and terminate with the ends in spaced relationship. Said bolt 152 and the arms 156 are slideable in a casing 158 which in turn is positioned in a circular hole bored transversely into the side edge 155 of the door and which casing is fixed to the door by means of a fixing plate 159 on one end of the casing.

The end of the casing opposite to said fixing plate is closed off and within the casing are parallel walls which form grooves 158a in which the bolt arms 156 are slidably mounted and guided. In said end region the casing 158 has transverse aligned ports 161 and on both sides of said ports 161 and spaced therefrom are bolt holes 162. The actuating slide 163, described hereinafter, extends through the ports 161 and is slidably therein. The slide 163 preferably has a longitudinal rib 164 thereon which is engaged in notch-like recesses 161a provided in the ends of the ports 161 and whereby the guiding action of the ports on slide 163 is further assisted and the slide is strengthened.

The actuating slide 163 is of elongated form and of substantially rectangular cross-sectional shape having similar V-shaped recesses 165 at corresponding positions in the opposite larger faces and having between the recesses a reduced or web-like region 166. In the slide 163 is an axial bore 167 in which a locking rod 168 is rotatably positioned, said bore 167 intersecting the recess or recesses 165 provided in the slide 163.

The intermediate region of the locking rod 168 has a reduced cross-section 169, and has a radial projection 170 (see FIGURE 17). Said reduced cross-section portion 169 of rod 168 lies within the web 166 of the slide 163 and has the maximum dimension thereof less than the distance between the ends of projections 157 to permit retraction of the bolt 152 when the slide 163 is actuated or pressure is applied on the projecting end 154 of the bolt 152, such as when the bolt strikes a striker plate in a door jamb or the like on closing of the door or the like.

The radial projections 170 on the rod 168 extend transversely of the rod so that they are engageable with a transversely undisplaceable part of the fastening device assembly, which part in this particular form is the transverse faces of one of the projections 157 on the arms 156 on bolt 152. The end 171 of the rod is couplable to a coacting end of a barrel 188 of a key operated rotatable locking device 173, whereas the opposite end 172 of the rod has fixed thereto a turnable knob 185 or the barrel of another key operated locking device, in which case the shaping of such end 172 would be modified, as will be described with reference to FIGURES 23 and 24.

The said V-shaped recesses 165 have convergently arranged oblique faces 160 on which faces the faces of projections 157 which are directed towards the bolt 152 are slidably movable for retracting the bolt by a wedging action when the said slide 163 is displaced in the direction of its own axis.

In one form of construction, the rod 168 has a single radial projection 170a (FIGURES 25 and 27) which, in the locking position of the rod, bears against one outside face of the latch bolt casing 158 at a position above or below the port 161 by extending through an aperture 184 in the slide 163. When the projection 170a is thus engaged, the sliding action of the slide 163 is stopped in one direction only. Alternatively, the radial projection may be positioned so as to engage an inside face of casing 158 as is the projection 170e of FIGURE 30. Such a radial projection can be positioned on the rod 168 in such a position that it is adapted to engage a side face of a bolt arm 156 or one of the perpendicular projections 157 as are the projections 17 of FIGURES 12 and 17. In a further modified form, such a radial projection may be positioned towards an end of the rod for engaging a part of a fixed handle 175 in which the slide 163 slides and wherein such slide is also guided. Such a radial exten-

sion can also be arranged to engage in a cavity or recess provided in the handle 175.

There can also be a plurality of projections on rod 168. An additional radial projection 170b can be provided diametrically opposite the radial projection 170a so that projections abut against two regions of the fastening device assembly which are not capable of transverse displacement for additional security. The aforesaid radial projections on the rod 168 block the axial movement of the rod, and consequently also the slide, in one direction only.

Where sliding movement of the slide 163 is to be blocked or locked in both directions, the rod 168 can be provided with an additional projection 170c or additional projections 170c and 170d (see FIGURE 27 and FIGURE 26) in axially spaced relationship relative to projection 170a or projections 170a and 170b. The radial projections 170a and 170c, or projections 170a, 170b and 170c, 170d, are disposed in spaced relationship for bearing engagement against the opposite sides of the bolt casing 158, the bolt arms 156 or projections 157.

In a modification of this form of construction, in order to block the sliding movement in both directions, the single radial projection 170e of FIGURES 30 and 31 can be made sufficiently long to engage opposed internal surfaces of the bolt casing 158, for example, walls forming the guide groove 158a for the bolt extensions 156. With this arrangement, diametrically opposed projections can also be provided to engage internal upper and lower parts of the bolt casing. However with such arrangement and the part 169 of rod 168 having a dimension such that the bolt projections 157 will clear the rod part 169 when the bolt moves, the projection 170, when in the operative position, forms a blocking element in the path of the projection 157 on latch bolt 152 whereby the latch bolt as well as the slide becomes locked and prevented from being retracted, thus providing "dead locking."

In the preferred arrangement of the rod, as is shown in FIGURE 17, the radial projection 170 is provided with a central notch 179 which has faces 179a for bearing engagement against the sides of a projection 157 when the rod is in its position in the slide.

To prevent free rotation of the rod 168, a pair of flat surface forming recesses 182, arranged at right angles to one another, are provided in the rod which are engaged by a leaf-like spring, detent, spring clip 183 or the like which in turn is located in a recess 180 provided in the slide 163.

In the aforesaid forms of the fastening device, in which the radial projection or projections on the rod 168 are disposed within the axial bore 167 of the slide 163, the recess or recesses or like cavities 184 are provided in the slide 163 through which the radial projection or projections are adapted to rise when the rod is rotated to the operative position, see FIGURE 29. The rotational movement of the rod 168 is limited to 90° and such cavity or cavities 184 form stop means for limiting the extent of such rotation.

In the preferred arrangement of FIG. 17, the rod 168 has a flattened center region in which notches 174 are provided to clear stop members in the bore of the slide which prevent axial movement of the rod relative to the slide and which limit the extent of rotation of the rod 169 within the slide 163, as in the embodiment of FIGS. 1-7. The central notch 179 is of such a limited depth that the part of the rod in the bottom of the notch can pass between projections 157 and can thus permit movement of the bolt 152. Thus the rod shown in FIGURE 17 is of a kind which does not lock the bolt in either the extended or retracted position. When the reduced intermediate portion of the rod is not required for locking the bolt in the extended or retracted position, such rod may be placed in its locking or blocking position before the door is placed in the closed position which, however, is not the case with a locking rod which causes the bolt

to become locked in the extended position such as in FIG. 30.

The rod 168 is of generally circular cross-sectional shape having substantially semicircular and/or flat cross-sectional regions at selected positions. The one end part 172 of the rod 168 is preferably of semicircular cross-sectional shape or is provided with a flat longitudinal face for engaging in non-rotational fashion in a knob 185 (which knob also serves as a press button). The opposite end 171 is flattened or rectangular in cross-section and has a deep transverse notch 186 adjacent the extreme end for engaging in hook fashion in a complementarily shaped recess 187 provided in the inwardly directed end of the barrel 188 of a pin or wafer type rotatable cylindrical key operated locking device rotatably and lockably located in a housing. The housing is received in a tubular end casing part 189 of the slide 163. Such a coupling provides for relative rotational movement to an extent of approximately 90° but beyond which limited extent such parts rotate together to the extent permissible by rotational stop means of the rod, which is also to an extent of 90°.

Where a barrel is used which is capable of satisfactory operation in any position, e.g. when inverted, the recess 187 has internally thereof a curved shelf-like region 190 which fits into the transverse notch 186 in rod 168 while adjacent such shelf-like region are formed faces 191 which bear on the flat faces on the rod end 171 for causing rotation of the rod when faces 191 press thereon. Pairs of faces 191 are located at right angles to one another to provide for the said relative rotational movement between the barrel and the rod as aforementioned. In the case of a key operated rotatable barrel locking device which is not satisfactory in operation when inverted, the recess 187a in the modification of FIGURES 21 and 22 opens outwardly in diametrically opposite sides of the inwardly projecting end of the barrel and a diametrically extending bar 192 is provided, instead of the shelf-like region 190, which fits into the transverse notch 186 of the rod 168. This provision is found to be desirable in the case of pin tumbler key operated rotatable locking devices. In both forms of construction, the rotatable lock part is placed in engagement with the rod by a transverse movement while disengagement in the transverse direction cannot take place due to the rotatable key operated lockable part being retained in the tubular end part 189 of the slide.

In the case of a pin tumbler type of key operated locking device of the known kind, the housing part thereof is positioned in the tubular end part 189 of the slide while the face of such locking device forms a pressure area on which slide displacing pressure is applied after unlocking the locking device with the aid of a key.

The tubular end part 189 of the slide is slidable in and guided in a transverse hole 195 of one handle 175. In the other handle 175, a hole is provided in which the knob 185 is slidably guided. The handles 175 are preferably fixed by screws or bolts 196 extending through holes provided in the handle on the inside of the door, through the door, through the spaced holes 162 of casing 158 and into screw threaded holes 197 of the handle 175 on the outside of the door. One of the screws 196 passes freely between the parallel bolt arms 156.

When a key operated locking device for rotating the rod 168 is required on both sides of the door, the end 172 of the rod 168 is provided with a flattened end tip part 199 (FIGURE 24) as well as the transverse notch 186. The coacting barrel or cylindrical part 188a of a key operated locking device, is provided in the inwardly directed end with a complementary shaped recess 187a, pairs of internal faces 191 and a diagonally positioned bar 192 into which the said end 172 of the rod is slid in a transverse direction and hooked as with the lock of FIGS. 21 and 22. Said lock with its housing is received in a casing 201. The casing 201 has a diametrically extending flanged groove

for sliding engagement with a complementary shaped end region of the slide for a coupling action. The coupling of the casing 201 to the slide and the coupling of the rod to the barrel 188a takes place simultaneously.

5 The casing 201 or tubular end part 189 of the slide 163 are shown to be of ellipse-like shape which prevents rotation of the casing of the lock while in addition the widths of the handles may be reduced. Other shapes can be used if desired.

10 A further feature of the invention resides in the construction of the bolt casing 158 in which at least one shallow transverse projection 193 is provided within the guide groove 158a for engaging a shallow recess 194 provided in the outwardly directed face of one of the arms

15 156 of the bolt 152 to prevent unintentional or accidental removal of the bolt from the casing 158. Preferably, projections 193 are provided on opposite sides of the casing 158 and both arms 156 of the bolt are provided with said recesses 194. Said projections 193 are conveniently integral with the casing, and on insertion of the bolt into the casing the arms 156 are deflected inwardly due to the resilient characteristics of the material of such arms so that the movement of the bolt will be limited by the spacing of

20 shoulders 198 formed at the end of each recess 194. To facilitate the insertion of the bolt into the casing, the ends of the bolt arms 156 are tapered or rounded off as at 203 so that when the bolt is forced into the casing the arms are deflected inwardly until the projections 193 engage in the recesses 194.

30 According to a further optional feature, the end 171 of the rod 168 can be provided with a fixed or uncouplable plug or barrel 205 (see FIGURE 27) of a non-locking kind and having a slot 206 or other shaped recess in the transverse face for engagement by a simple key, screw driver, coin, nail file or the like for unlocking. This feature is particularly suitable for an emergency fastening device such as may be used on bathroom doors, e.g. in hospitals, or the like which may require ready opening from the outside in case of an emergency.

35 A still further optional or additional feature resides in the provision of a slidable latch element on one or both the fixed door handles 175 and whereby the slide may be held or locked against movement. Such latch element conveniently consists of a small slide 207 (FIGURES 14 and 33) slidably retained in a complementarily shaped recess 208 provided in a fixed door handle 175 and having its movement resiliently restrained by a leaf spring, spring clip, detent or the like 209. The said latch element, when placed in an operative position, is adapted to engage a recess, hole, slit or transverse groove 216 in the knob 185. However, such latch element engaging recess or the like can also be provided in the slide or in the tubular end 189 of the slide 163. By the provision of such a latch element, the fastening device according to the invention may be readily locked without the aid of key means from one or both sides of the door so that unlocking cannot be effected with the aid of a key or on turning of the knob 185 on the opposite end of the slide. When it is required to engage and lock the knob 185, the locking action of the latch element 207 takes place when the knob 185 is turned to position the rod 168 in the locking or blocking position so that unlocking cannot take place from either side of the door unless such latch element has been manually retracted to its inoperative position.

40 As indicated above, said latch element may also be provided on the key operated lock element of the slide, in which case such element engages a cavity provided in the tubular part 189 of the slide 163.

45 This additional feature provides for additional security, such as where a door is situated on a passage and it is required, should anyone break into the room, that such person be confined to that room by being incapable of unlocking the lock to enter the passage.

50 55 60 65 70 75 It will be obvious that instead of the tubular end part

189 on the slide a knob may be provided where the fastening device does not require key operated locking means.

As with the embodiment of FIGS. 1-7, the slide is normally retained in its centralised position by means of compression springs 210 encircling regions of the slide and adapted to press on exterior side faces of the bolt casing 158 around the ports 161 and also bearing on shoulders 211 on the slide, the knob 185 or the casing 201. One of the springs 210, when in position maintains the coupling between casing 201 and the slide. The knob 185 is conveniently fixed on the rod end 169 by a set screw 212. The bolt 152 is resiliently biased to the extended position by a light spring 213 which has one end located in a recess 214 provided in the bolt 152 whereas the other end of the spring is located in a shoulder forming recess 215 provided in an intermediate part of the casing 158 and more particularly at the position where the interior of such casing 158 reduces to form the guide groove 158a. Said recess 214 opens outwardly in a transverse direction to facilitate the placing in position of the spring 213.

By positioning the bolts 196 so that they pass through the spaced holes 162 of the bolt casing 158, correct alignment of the handles and slide with the ports 161 is ensured should the hold extending transversely through the door not be perpendicular to the door faces and the axis of the bolt casing receiving hole.

According to a still further modification of the invention, recesses 220 (see FIGURE 34) are provided on either side of the apex of the V-shaped recesses 165 to provide weakened regions on the slide. Should an end of the slide be hammered in an attempt to force the lock, these regions can break away when the material of the walls between the recesses 165 and 220 collapses and a perpendicular face will thus be formed for engaging the arms 156 and projections 157 of the bolt, thus making it entirely impossible to retract the latch bolt without hammering the entire fastening device out of the door.

The locks described with reference to the drawings are operative from both sides of the door. Such locks can be readily constructed for operation from one side of the door only such as for use on cupboard doors or the like. With such a modification of the invention and when a key operated lock is required, the rod 105 or 105a terminates at the end 112 of the slide 13 or 13a, while knob 24 and associated spring 139, and also the handle 46 will not be required (see FIGURES 1-6). If a lock of this kind is not required to be of a key operated kind, the cylindrical extension 19 and the cylindrical lock barrel 40 are not provided. In both these cases, the V-shaped notch or notches 15 provide a stop forming transverse wall to limit the motion of the slide in one direction while only one spring 139 would be used.

The lock according to this invention may be used in doors of different thicknesses (within limits) without requiring modification or substitution of different sized parts. Furthermore, the lock according to this invention is easily assembled and the possibility of incorrect assembly avoided.

The fastening device according to this invention fits all kinds of doors without requiring substitution of parts or dismantling to turn parts to suit the swing of the door. In addition, the lock according to this invention is made up of a small number of parts to keep the manufacturing costs down to a minimum. The lock according to this invention also provides a fastening device which, if the key is lost, is not useless as it can still be locked from the inside of a room by the turning of the knob 24 to the locking position.

It will of course be understood that the parts of the various modifications can, with changes which will be obvious from the foregoing description, be substituted for similar parts in other modifications, and the various modifications can be simplified by the elimination of non-essential parts, such modifications and simplifications

being within the scope of the invention as defined in the claims appended hereto.

I claim:

1. A fastening device for doors and the like, comprising in combination a bolt casing, a spring biased latch bolt slidably mounted within said bolt casing, the end of said bolt within the casing having at least one arm extending in the axial direction from the end of said latch bolt, said arm having a projection on the end thereof extending diametrically of said latch bolt and having two converging faces on the side of the projection toward said bolt, a guided actuating slide extending transversely through the casing and adjacent said arm and between the latch bolt and the projection, said actuating slide having a V-shaped recess in at least one longitudinal side of the slide, said V-shaped recess having two converging faces with which the converging faces of said projection engage for displacing the bolt in the direction of its axis on displacement of the slide in the direction of its own axis, said slide having an axial bore therethrough intersecting the V-shaped recess at a point spaced from the apex thereof, a rod-like element located in the bore of said actuating slide and rotatable about its axis at least through 90°, said rod-like element having a portion of reduced cross-sectional shape along a part of its length having a dimension at least in one direction transverse to the length of the rod-like element no greater than the distance from the end of said projection on said latch bolt arm to the bottom of the axial bore in said actuating slide, said reduced cross-sectional portion in one rotational position of said rod-like element allowing passage of said projection on said arm past said rod-like element, and at least one projection on said rod-like element extending in a direction transverse to the length of said rod-like element and perpendicular to the said one direction and engageable with a part of said fastening device other than said slide to block movement of said slide relative to said latch bolt when said rod-like element is in another rotational position 90° from said first rotational position.

2. A fastening device for doors and the like, comprising in combination a bolt casing, a spring biased latch bolt slidably mounted within said bolt casing, the end of said bolt within the casing having a pair of parallel arms extending in the axial direction from diametrically opposite positions on the end of said latch bolt, each of said arm having a projection on the end thereof, said projections extending toward each other and having the ends spaced from and opposed to each other, at least one of said projections having two converging faces on the side of the projection toward the bolt, a guided actuating slide extending transversely through the casing and through the space between said arms and between the latch bolt and the projections, said actuating slide having a V-shaped recess in at least one longitudinal side of the slide, said V-shaped recess having two converging faces with which the converging faces of said at least one projection engage for displacing the bolt in the direction of its axis on displacement of the slide in the direction of its own axis, said slide having an axial bore therethrough intersecting the V-shaped recess at a point spaced from the apex thereof, a rod-like element located in the bore of the actuating slide and rotatable about its axis at least through 90°, said rod-like element having a portion of reduced cross-sectional shape along a part of its length having a dimension at least in one direction transverse to the length of the rod-like element no greater than the distance between the spaced opposed ends of said projections, said reduced cross-sectional portion in one rotational position of said rod-like element allowing passage of said projections on said arms past said rod-like element, and at least one projection on said rod-like element extending in a direction transverse to the length of said rod-like element and perpendicular to the said one direction and engageable with a part of said fastening device other than said

slide to block movement of said slide relative to said latch bolt when said rod-like element is in another rotational position 90° from said first rotational position.

3. A fastening device for doors and the like comprising in combination a bolt casing, a spring biased latch bolt slidably mounted within said bolt casing, the end of said bolt within the casing having a pair of parallel arms extending in the axial direction from diametrically opposite positions on the said end of said latch bolt, each of said arms having a projection on the end thereof, said projections extending toward each other and having the ends spaced from and opposed to each other, at least one of said projections having two converging faces on the side of the projection toward the bolt, a guided actuating slide extending transversely through the casing and through the space between said arms and between the latch bolt and the projections, said actuating slide having a V-shaped recess in one longitudinal side of the slide, said V-shaped recess having two converging faces with which the converging faces of said at least one projection engage for displacing the bolt in the direction of its axis on displacement of the slide in the direction of its own axis, said slide having an axial bore therethrough intersecting the V-shaped recess at a point spaced from the apex thereof, a rod-like element located in the bore of the actuating slide and rotatable about its axis at least through 90°, said rod-like element having a portion of reduced cross-sectional shape along a part of its length with a dimension in one direction transverse to the length of said rod-like element no greater than the distance between the spaced opposed ends of said projections and having a dimension in the direction perpendicular to said one direction and transverse to the length of said rod-like element greater than the distance between the opposed ends of said projections, whereby the rod-like element can be rotated to place it in either of two alternative positions, in one alternative position preventing movement of said one projection along the surfaces of said V-shaped recess and in the other position permitting movement of said one projection along the surfaces of said V-shaped recess.

4. The combination as claimed in claim 3 in which said portion of said rod-like element having the reduced cross-sectional shape is solid in the central portion of the length thereof, and in one alternative position preventing passage of said projections past said portion of said rod-like element and in the other position permitting passage of said projections past said rod-like element.

5. The combination as claimed in claim 3 in which said portion of said rod-like element having the reduced cross-sectional shape is centrally notched with the notches having a dimension along the rod-like member slightly greater than the thickness of said projections transversely of the arms on said latch bolt, the notches being on opposite sides of said rod-like element in positions opposed to each other and extending into said rod-like element to reduce the greater dimension thereof to the same size as the lesser dimension thereof, whereby in one alternative position the movement of said one projection along the surfaces of said V-shaped recess is prevented while the projections are free to move past said rod-like member, and in the other position the one projection is free to move along the surface of the V-shaped recess while the projections are free to move past said rod-like member.

6. A fastening device as claimed in claim 2 in which said actuating slide has a tubular extension on one end thereof, said tubular extension having a key operated locking device connected to said rod-like element and constituting means on one end thereof for rotating the rod-like element.

7. A fastening device as claimed in claim 2 in which said actuating slide has a tubular extension on one end thereof, a key operated locking device in said tubular extension connected to said rod-like element and constituting means on one end thereof for rotating the rod-like element, said key operated locking device having spring

means connected thereto and to said tubular extension for returning said key operated locking device to a given position when it is rotated in either direction from said position.

5 8. A fastening device as claimed in claim 7 in which said key operated locking device has a circumferential groove therein and said spring means comprises a coiled spring in said groove with the ends thereof attached to said key operated locking device, and said tubular extension has a projection extending into said groove and engaging the central portion of said spring to keep it fixed relative to said projection.

10 9. A fastening device as claimed in claim 2 in which said actuating slide has a tubular extension on one end thereof, a key operated locking device in said tubular extension and constituting means on one end thereof for rotating the rod-like element, said key operated locking device having a cylindrical recess on the end thereof toward said rod-like element and at least one projection extending into said recess having two surfaces thereon at right angles to each other, said rod-like element extending into said cylindrical recess and having a flat surface thereon engageable by said surfaces on said projection eccentrically of the axis of said rod-like element for turning said rod-like element.

15 10. A fastening device as claimed in claim 2 in which said actuating slide has a tubular extension on one end thereof, a key operated locking device in said tubular extension and constituting means on one end thereof for rotating the rod-like element, said tubular extension having diametrically opposite circumferentially extending slots therein, said key operated locking device having a cylindrical recess in the end thereof toward said rod-like element and having diametrically opposed slots through

20 30 the walls of said cylindrical recess, a wafer-like element slidable in said slots in said tubular extension and said key operated locking device and having a trapezium shape with the ends inclined at equal angles, the maximum length of said wafer-like element being equal to the in-

25 side diameter of said tubular extension, spring means engageable with said wafer-like element urging it in one direction along said slots in said cylinder lock, and the end of said rod-like element extending into said cylindrical recess having two faces at substantially right angles to each other, each face having a notch therein joining the notch in the other face, said wafer-like element having an aperture therethrough through which said end of said rod-like element extends with the notches engaging around the edges of said aperture, said notches being of different depths for moving said wafer-like element in one direction or the other against the spring means for engaging the ends of the wafer-like element in one or the other of the slots in the tubular extension depending on the position of said rod-like element.

30 55 11. A fastening device as claimed in claim 2 and means for applying pressure to said slide comprising a tubular extension on one end of said slide, and a knob on the end of said rod-like element at the end of said slide opposite said tubular extension, said tubular extension and said knob each having an outwardly projecting flange thereon and a spring therearound with one end against said flange, and a pair of handle means for mounting on a door and each having a bore therein into which said tubular extension and said knob fit respectively, said handle means each having an inwardly extending flange thereon against which said springs bear for centering said slide.

35 60 65 12. A fastening device as claimed in claim 2 and means for applying pressure to said slide comprising a tubular extension on one end of said slide, and a knob on the end of said rod-like element at the end of said slide opposite said tubular extension, said tubular extension and said knob each having an outwardly projecting flange thereon and a spring therearound with one end against said flange, the other ends of said springs bearing against said bolt casing for centering said slide.

13. A fastening device as claimed in claim 2 in which said actuating slide has a flat spring extending across the bore therethrough, and said rod-like element has a pair of notches therein adjacent each other in the peripheral direction of said rod-like element, said notches each having a flat bottom which is perpendicular to the flat bottom of the other notch, and in which notches said spring engages for retaining said rod-like element in one of two positions against unintentional movement from said position.

14. A fastening device as claimed in claim 2 in which said actuating slide is substantially rectangular in cross-section at least in the central portion thereof, and said V-shaped recess extends from one wide face of said slide.

15. A fastening device as claimed in claim 14 in which said V-shaped recess extends completely through said slide from one wide face to the other, and a web is provided at the center of said slide, said web having an aperture therethrough aligned with said bore in said slide.

16. A fastening device as claimed in claim 15 in which said V-shaped recess extends only part way.

17. A fastening device as claimed in claim 2 in which the rod-like element has a knob coupled to one end thereof, said knob having a non-circular cross-sectional shape.

18. A fastening device as claimed in claim 2 in which the rod-like element has a knob coupled to one end thereof and a key operated locking device coupled to the other end thereof.

19. A fastening device as claimed in claim 2 in which the rod-like element has a key operated locking device coupled to each end thereof.

20. A fastening device as claimed in claim 2 in which the rod-like element has a knob coupled to each end thereof.

21. A fastening device as claimed in claim 2 in which the rod-like element has an operating means at only one end thereof, said operating means being taken from the group consisting of a key operated locking device and a knob.

22. A fastening device as claimed in claim 2 in which said actuating slide has a rib along one edge thereof, said bolt casing having diametrically opposite ports through which said actuating slide passes, said ports each having a notch in the edge thereof in which said longitudinal rib is engaged for guiding and locating said slide relative to said bolt casing.

23. A fastening device as claimed in claim 2 in which one end of said rod-like element has a reduced cross-section and has a flattened shape and has a transverse notch adjacent said one end, and said fastening device further comprises a rod rotating means having a recess in one end thereof and a transverse part in said recess engaged by the notch in the said one end of said rod-like element for coupling said rod-like element and said rotating means for rotation together when said rotating means is rotated and for rotation of said rod-like element while said rotating means remains fixed when the rod-like element is rotated from the other end, said rotating means having a groove therein extending parallel to the axis for enabling the rod-like element to be inserted into the recess and engaged with said transverse part.

24. A fastening device as claimed in claim 2 in which said bolt casing has at least one inwardly extending projection therein and one of said arms on said bolt has a shallow recess on the surface thereof opposed to said inwardly extending projection, whereby the movement of the bolt is limited by the abutment of the inwardly extending projection on the bolt casing with the ends of the recess on the arm.

25. A fastening device as claimed in claim 24 in which said bolt casing has parallel walls therein in the end remote from the end from which the bolt projects, said parallel walls guiding said arms on said bolt, said inwardly extending projection on the bolt casing extending into the space between said parallel walls, and a further in-

wardly extending projection on said bolt casing diametrically opposite said first mentioned projection, and the other of said arms also having a shallow recess therein in which said further projection engages.

5 26. A fastening device as claimed in claim 2 which further comprises a non-locking barrel-like rotatable part engaged with one end of said rod-like element and bearing on said slide, said rotatable part having a non-circular depression in the face remote from the end engaged with 10 said rod-like element, said depression being for engagement by a non-circular tool for turning the rotatable part to turn said rod-like element.

15 27. A fastening device as claimed in claim 2 which further comprises at least one door handle adapted to be secured to one side of a door and having an aperture therethrough in which said slide and locking rod are guided, and a slideable latch element on said door handle movable toward and away from said slide and locking rod and engageable therewith for locking said slide against movement in an axial direction.

20 28. A fastening device as claimed in claim 2 which further comprises a pair of door handles adapted to be mounted on opposite sides of a door and having aligned apertures through which said slide and rod-like element 25 are guided, one of said handles having spaced parallel holes extending parallel to said apertures and the other of said handles having tapped holes aligned with said spaced parallel holes in the one handle, and a pair of screw-like securing elements extending through said spaced parallel holes, through said bolt casing and into said tapped holes, one of said securing elements passing between said arms on said bolt.

35 29. A fastening device as claimed in claim 2 in which said slide has further recesses therein adjacent the apex of said V-shaped recess for forming a weakened portion of said slide, whereby when excessive impulses are applied to the ends of said slide in an attempt to force the fastening device, the weakened portion of the slide will break and transverse faces will be formed which will 40 abut against said projections on said arms on said bolt to prevent movement of said slide.

30. A fastening device for doors and the like, comprising in combination a bolt casing, a spring biased latch bolt slidably mounted within said bolt casing, the end of said bolt within the casing having a pair of parallel arms extending in the axial direction from diametrically opposite positions on the end of said latch bolt, each of said arms having a projection on the end thereof, said projections extending toward each other and having the ends spaced from and opposed to each other, at least one of said projections having two converging faces on the side of the projection toward the bolt, a guided actuating slide extending transversely through the casing and through the space between said arms and between the latch bolt and the projections, said actuating slide having at least a central portion with a cross-sectional shape with a dimension in one direction transverse to the axis of the slide which is greater than the dimension perpendicular to said one direction and transverse to the axis 50 of the slide, said actuating slide having a V-shaped recess in at least one longitudinal side of the slide, said V-shaped recess having two converging faces with which the converging faces of said at least one projection engage for displacing the bolt in the direction of its axis 55 on displacement of the slide in the direction of its own axis, said slide having an axial bore therethrough intersecting the V-shaped recess at a point spaced from the apex thereof, a rod-like element located in the bore of the actuating slide and rotatable about its axis at least 60 through 90°, said rod-like element having a portion of reduced cross-sectional shape along a part of its length having a dimension at least in one direction transverse to the length of the rod-like element no greater than the distance between the spaced opposed ends of said projections, said reduced cross-sectional portion in one rota-

tional position of said rod-like element allowing passage of said projection on said arms past said rod-like element, and said rod-like element having at least one projection thereon along the length thereof at a point within said central portion of said slide and extending transversely of said actuating slide a distance sufficient for engagement with a portion of said fastening device other than said slide to block movement of said slide relative to said latch bolt when said rod-like element is in another rotational position 90° from said first rotational position.

31. A fastening device as claimed in claim 30 in which there is only a single projection on said rod-like element.

32. A fastening device as claimed in claim 31 in which said single projection is adjacent said arms extending from said bolt when said rod-like element is positioned in said slide, whereby when said rod-like element is rotated through 90° said projection will engage one of said arms and prevent movement of said slide.

33. A fastening device as claimed in claim 31 in which said single projection is aligned with said projections on said arms extending from said bolt when said rod-like element is positioned in said slide, whereby when said rod-like element is rotated through 90° said projection will block said projections and block movement of said bolt as well as of said slide.

34. A fastening device as claimed in claim 30 in which there are a plurality of projections, said projections being spaced from each other along the length of said rod-like element.

35. A fastening device as claimed in claim 34 in which there are at least two projections, said projections being spaced from each other along the length of said rod-like element a distance equal to the dimension of said bolt casing in the direction in which said slide passes through said casing, whereby when said rod-like element is rotated through 90° said projections will engage against the outside of said bolt casing and block movement of said slide.

36. A fastening device as claimed in claim 34 in which

there are at least two projections said projections being spaced from each other along the length of said rod-like element a distance slightly less than the dimension of said bolt casing in the direction in which said slide passes through said casing, whereby when said rod-like element is rotated through 90° said projections will engage against the inside of said bolt casing and block movement of said slide.

37. A fastening device as claimed in claim 34 in which there are at least two projections, and said fastening device further comprises a pair of door handles adapted to be mounted on opposite sides of a door and having aligned apertures through which said slide and rod-like element are guided, said handles each having a recess therein engageable by a projection on said rod-like element, whereby when said rod-like element is rotated through 90° said projection will engage in said recesses in said door handles and block movement of said slide.

38. A fastening device as claimed in claim 34 in which there are at least two projections, said projections being spaced from each other along said rod-like element a distance only slightly greater than the dimension of said projections on said arms on said bolt in the direction perpendicular to the axis of said bolt, whereby when said rod-like element is rotated through 90° said projections will engage the opposite sides of one of said projections on the arms of said bolt and block movement of said slide.
